COMBINATION SASH FASTENER AND ANTRATTLING DEVICE

Leonard A. Pranevich, Pittsburgh, Pa.

Application March 29, 1934, Serial No. 718,046

3 Claims. (Cl. 292—60)

This invention relates broadly to closure fasteners and is an improvement over that type of closure fastener forming the subject matter of my co-pending application Serial No. 667,086 filed

5 April 26, 1933.
An object of the present invention is to provide a device of the character above mentioned which will not only serve as an efficient fastener for securing the upper and lower sashes of a window locked either in closed position, or in a partly open position for the purpose of ventilation, but to also admirably serve as a means to prevent rattling of the window sashes in either of the positions mentioned.

15. A still further object of the invention is to provide a device which can be readily applied to the window sashes without defacing the same to any material extent, and which can also be adjusted so as to efficiently operate regardless of 20. the condition of the sashes due to sagging thereof.

The invention together with its objects and advantages will be best understood from a study of the following description taken in connection with the accompanying drawings wherein:

25. Figure 1 is an elevational view illustrating the application of the invention with the window sashes in fully closed position.

Figure 2 is a view similar to Figure 1 illustrating the application of the invention with the lower sash in a partly raised position for ventilation purposes.

Figure 3 is a similar view illustrating the application of the invention with the upper and lower sashes in partly open position for ventilation purposes.

Figure 4 is an enlarged detail view taken substantially on the line 4-4 of Figure 1.

Figure 5 is an enlarged sectional view taken through the device.

40 Figure 6 is a transverse sectional view taken through a portion of the device.

Figure 7 is an elevational view of the device with certain parts removed.

45. Figure 8 is a perspective view of an adjustable plate. Figure 9 is a perspective view of a bolt.

Figure 9 is a perspective view of a bolt.
Figure 10 is an elevational view of a portion of
the lower bar.

50. Figure 11 is a sectional view taken substantially on the line 11-11 of Figure 10.

Figure 12 is an elevational view of a second scraper bar.

Figure 13 is a detail sectional view taken substantially on the line 13-13 of Figure 12, and

Figure 14 is a fragmentary vertical sectional view taken at right angles to Figure 11.

Referring to the drawings by reference numerals it will be seen that the numerals 5 and 6 indicate, respectively, the upper and lower sliding sashes of a window mounted within a frame, one side rail of which is designated by the numeral 7.

In accordance with the present invention there is secured to the inner side of the frame of sash 5, adjacent the rail 7, a keeper plate 8 which is substantially channel shaped in cross section and has the sides thereof provided with oppositely extending apertured flanges 8' whereby the bar may be secured by suitable fastening elements to the sash frame. The web of the plate 8 is provided with a vertical series of spaced apertures or slots 9 which are substantially oblong, and are elongated transversely of the plate 8 as clearly shown in Figures 12 and 13.

A second keeper plate or bar 10 is also provided, and the same is substantially channel shaped in cross section as shown in Figure 11, and is provided along one side and the ends thereof with an apertured flange 11 whereby said plate may 25

be secured by suitable fastening elements 12 to the inner face of the aforementioned rail 7 of the window frame. The bar 10 is provided with a vertical series of spaced apertures 13 which are substantially of the same shape as the apertures 30

9 but which, as shown in Figure 10 are elongated longitudinally of the plate 10. A pair of plates 14, 15 are disposed at right angles to one another and are permanently united at one edge, pref-

erably by being integral one with the other. The
plates 14 and 15 extend at right angles to each
other, the plate 14 being located on the top of
the meeting-rail of the lower sash and the plate
15 being located at the front of said meeting
rail, said plate being firmly secured to the meet-
ing rail by screws or other suitable fastening ele-
ment.

ment. Each plate 14, 15 is provided with a bolt casing 16 that is permanently united with its plate, preferably by being integral therewith. Each bolt casing 16 contains a bolt 17 that is normally urged outwardly of its casing through the medium of a spring 18. At its free end the bolt is flattened on diametrically opposite sides thereof to provide a head 17a of substantially rectangular formation in cross section and provided with a notch 19. 45 50

It will be noted that the head of the bolt 17 operating in the bolt casing 16 of plate 14 is adapted to engage with the plate 8 while the bolt 55

associated with the plate 15 is adapted to engage with the keeper bar or plate 10, the first named bolt serving to lock the two sashes to each other, and the second named bolt serving to lock said sashes to the window frame.

In this connection it will also be appreciated that when the head 17a of a bolt 17 is projected into the aperture of the proper keeper bar 8, or 10, as the case may be, and the bolt subsequently rotated, notch 19 will engage the keeper bar at one edge of the aperture with the result that a binding effect is produced to the end that the window sash, or sashes, as the case may be will be securely held against rattling.

Each bolt casing 16 is provided with an elongated slot 20 that connects a relatively elongated keeper notch or recess 21 with a relatively short keeper notch or recess 22.

Each bolt 17 has screw threadedly engaged therewith a knob 23 the shank of which is adapted to operate in the slot 20 upon sliding movement of the bolt 17, and with the bolt 17 in a projected position to move into the notch 21 upon rotation of the bolt; and with the bolt in a retracted position, to move into notch 22 upon rotation of the bolt. With the knob 23 engaged in the recess or notch 22 bolt 17 will be held in a retracted position against the action of spring 18.

From the above it will be apparent that with the bolt 17 in a projected position the same will be permitted a great deal of play due to the length of the notch 21. As a result of this there would be no positive holding of the window sash against rattling. To overcome this defect there has been provided for each of the bolt casings 16 an adjustment plate 24 that slidably rests on the base plate of the bolt casing 16 as suggested in Figures 5 and 6. The plate 24 is provided with a slot 25 to accommodate a screw 26 that is threaded into the base plate and which is adapted to bind upon the plate 24 in a manner securing the same at the desired adjustment. At one edge thereof the plate 24 is provided with a pair of spaced flanges which are spaced a distance apart materially less than the distance between the opposite ends of slots 21. The aforementioned flanges include a flange 27 and a flange 28 which latter flange is about one-half the width of the flange 27 and is arranged midway between the flange 27 and the end edge of the plate 24 farthest remote from the flange 27. The flanges 27, 28 are suitably curved to overlie the bolt casing 16 as shown in Figure 6, and these flanges 27, 28 serve to provide between them a notch for accommodating the knob 23 of the bolt at the proper projected position and with very limited play. It will thus be seen that with the notch 19 in the head of a bolt 17 engaged with the proper keeper plates 8, 10, and the knob 13 of the bolt engaged in the space between the flanges 27, 28, and with plate 24 at the properly adjusted position, a rigid locking of the two sashes together, and of the lower sash with the window frame is obtainable to an extent tending to eliminate rattling of the window sashes.

It will be noted that the apertures 9 in plate 8 are of a length corresponding substantially to the width of the channel portion of the plate so that there are no end edges with which the slot

19 of the bolt 17 will engage when the bolt has been rotated and is retracted for the purpose of releasing the upper and lower sashes.

To guard against the notch 19 of the bolt engaging with the plate 10 at the upper edge of one of the apertures 13, when said bolt is rotated for releasing the lower sash, said plate 10 at the upper edge of each of the apertures 13 has a lip 13b pressed inwardly therefrom as best shown in Figure 14.

To facilitate the raising and lowering of the upper sash each plate 8 is provided with a suitably arranged lug 8b providing a finger hold in a manner thought apparent.

It will also be understood that when the sashes are in fully closed position the upper sash will be forced upwardly and the lower sash forced downwardly into a tightly closed position upon rotation of the bolt 17 operating in the housing 16 in the operation of engaging the notch in 20 the bolt with an edge of the slot 9 of said plate, into which the head of the bolt is projected, for the purpose of locking the sashes in their closed position.

Having thus described my invention, what I claim as new is:

1. A sash fastener consisting of a bolt casing provided in the wall thereof with a slot and a pair of notches one of which is longer than the other, a spring pressed bolt contained within the bolt casing and having a knob operating in the slot and adapted to be, upon rotation of the bolt in one direction, engaged with a selected one of said notches, and an adjustment plate slidably engaged with the bolt casing and having a flange part overlying the bolt casing and provided with a notch of less length than the longest of the first named notches and adapted to receive the knob of the bolt when the bolt is in a projected position for holding said bolt at the desired adjustment in the last named position thereof.

2. A combination sash fastener and anti-rattling device comprising a right angular plate, each member of which has a bolt casing connected thereto, said bolt casing having a longitudinal slot provided with notches at its end, one of the notches being of greater length than the other of the notches, a bolt working in said bolt casing and having a laterally projecting knob, a slide plate on the member of the right angular plate adjacent to the bolt casing, means for securing the slide plate at the desired adjustment, said slide plate having a pair of spaced apart curved flanges disposed concentric to the bolt casing and overlying the longest notch, said flanges being adapted to receive therebetween the knob of the bolt.

3. A combination sash fastener and anti-rattling device, including in combination, a plate, a bolt casing mounted on said plate and provided with a longitudinal slot, a bolt operating in the bolt casing for sliding and rotative movement, and an adjustment plate slidably mounted on the first named plate and having substantially closely spaced stop flanges overlying the bolt 65 casing and between which flanges the knob of the bolt is receivable for securing the bolt at the desired adjustment.
